JAN SZCZEPANIK, OF VIENNA, AUSTRIA-HUNGARY, ASSIGNOR TO SOCIÉTÉ DES INVENTIONS JAN SZCZEPANIK & CO., OF VIENNA, AUSTRIA-HUNGARY, A FIRM.

ELECTRICAL JACQUARD MECHANISM FOR LOOMS.

SPECIFICATION forming part of Letters Patent No. 727,023, dated May 5, 1903.

Application filed September 24, 1900. Serial No. 30,990. (No model.)

To all whom it may concern:

Be it known that I, JAN SZCZEPANIK, a subject of the Emperor of Austria-Hungary, residing at Vienna, in the Province of Lower Austria, in the Empire of Austria-Hungary, have invented certain new and useful Improvements in Electrical Jacquard Mechanism for Looms: and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to an improved arrangement of the electromagnets in electrical jacquards which enables the magnet to be easily changed without considering the connections, and consequently enables the connections of the electromagnet to be easily altered. The electromagnets are arranged in such a way that in consequence of the formation of a ring of lines of force one armature cannot influence the adjacent armatures.

Figure 1 of the accompanying drawings shows, by way of example, the complete arrangement of the electromagnets in an electrical jacquard the electromagnets of which control the movement of the needle as determined by an electrical templet. Fig. 2 is a horizontal section of the magnet-box. Fig. 3 shows one of the electromagnets in longitudinal section.

The electromagnets *a*, which act in the usual manner on the armatures *d*, that control the needle *b* of the jacquard *c*, and release them when influenced by the magnets, are arranged in holes in an electrically-conducting magnet-box *f* and bear with their outer ends on contact-buttons *g*, which are pressed by springs *h* against the ends of the electromagnets. The pins *i*, carrying these buttons *g*, pass through a contact-board *j* and are connected, by means of clamped conducting-wires *k*, with pins *m*, arranged in a second contact-board *l* and provided in a similar manner with spring contact-buttons *n*. Each of the contact-buttons *n* is spring-pressed against a

conducting bell-crank lever *o'* of the selecting device *p*, the movable members *o* of which rest on the movable templet *q*. There is one finger *o* connected to its corresponding bell-crank lever *o'*, each of the latter having a single projection *o²* contacting with its respective button *n*. The fingers *o* are thin conductor-plates having at their hinge end a circular cut-away portion that is more than a half-circle. This recess fits over the boss 20 of the upturned lower ends of the conducting-levers *o'*. These upturned ends are circular, from which segments have been cut on each side of the center to form parallel chords. When the free ends of the fingers *o* are lifted to a sufficient extent, they can be slid into position on the circular portions 20 and assume the position indicated in Fig. 1, their ends resting on the templets *q*. This templet comprises, as usual, a metal plate which conducts at portions left bare, but does not conduct at other places which are covered with an insulating material. Underneath the templet there is arranged the current-supplying lever *r*, which is in contact with it and is connected to the current-supply wire *s*, while the return-wire *t* is connected with a terminal *u* on the magnet-box.

When a contact-lever *o* touches a bare or conducting place on the templet, the circuit is closed and the current flows from *s* through *r* to the templet *q*, through the corresponding contact-lever *o* and the corresponding contact-button *n* and wire *k* to the second corresponding contact-button *g*, and then through the corresponding electromagnet *a* to the magnet-box *f*, thence to the terminal *u*, and back to *t*. The electromagnets are thus selectively energized. The grid *d'*, that moves the armatures *d*, one in each opening *d²* for each magnet *a*, is vertically movable between the needle-board *b'* and the magnet-box, so that said armatures will be moved into alignment with their respective magnets. When so moved, the energized magnets (all of those shown in Fig. 1 are supposed to be energized) will attract the armatures and hold them. The grid *d'* is then moved down or dropped into the position shown in Fig. 1, the openings in the grid being larger than

the magnets, so that each armature that has been alined with its respective energized magnet will be held thereby to cover the opening in the needle-board *b'* and prevent 5 the needle from being moved in, thereby holding the respective hooks out of engagement with their griffs. The needles *b* are normally held retracted, and after the armatures have been selectively held in place 10 those so held act as distance-pieces, so that when the needles *b* are moved toward the magnets *a* those needles opposite the spaces not occupied or filled by armatures will enter them.

15 By means of the arrangement described the connections of the electromagnets can be easily altered, since the contact-boards can be removed and others substituted therefor. Furthermore, a machine with a large number 20 of lifting-wires can work a machine with a small number, if all of the electromagnets operating the superfluous needles are cut out by removing their contacts.

In order to permit of the described course 25 of the current and to prevent an excited magnet from influencing the adjacent magnets, the magnets are made as tubulated magnets of special construction. Fig. 3 shows such a tubulated magnet on a larger scale.

30 The conducting magnet-core *1* is surrounded by the winding *2* and is inclosed in a conducting tubular casing *3*, which is firmly connected to the core by means of a screw *4*.

The annular space for the winding *2* between 35 the core and the casing is closed at one end by the enlarged end of the core and at the other by a ring *5*.

To the enlarged end of the core there is secured, by means of a screw *7*, that passes 40 through an insulating-sleeve *6*, a hollowed-out contact-button *8*, which is completely insulated from the core by means of a disk *9*, made of non-conducting material. Between the contact-button *8* and the insulating-disk 45 *9* one end of the winding is clamped, while the other end of the winding is soldered or otherwise connected to the core at *10*. The current flows, therefore, from the spring contact-button *g* of the board *j* to the contact- 50 button *8* of the electromagnet, thence to the core through the winding *2*, that surrounds it and excites it, and from the core through the casing *3* to the magnet-box *f*, in order to return in the manner hereinbefore described 55 from the magnet-box to the return-wire *t*.

I claim—

1. In a jacquard mechanism, the combination with the needles and needle-board, of a series of stationary magnets arranged to operate 60 said needles, a contact, a flat electrical card, and a series of fingers adapted to receive a slight rotation by reason of the passage of the card thereunder, each in electrical connection with a magnet and arranged to touch said card, substantially as described.

65 2. In an electrical jacquard mechanism, the combination with the needles and needle-

board, of an electrically-conductive magnet-board and a series of magnets held in said board, and electrically connected thereto, 70 said magnet and needle-boards independently removable, substantially as described.

3. In an electrical jacquard mechanism, the combination with the needles and needle-board, of a contact-board, contacts held therein, an electrically-conductive magnet-board and electromagnets held in the same and in electrical connection therewith, said magnet-board arranged between the needle and contact-boards and each independently removable 80 from the others, substantially as described.

4. In an electrical jacquard mechanism, the combination with the needle-board, of a magnet-board formed of a conductor of electricity, magnets arranged in said board, and an electric pole of each magnet in contact with said board, substantially as described.

5. In an electrical jacquard mechanism, the combination with the needle-board, of a magnet-board, electromagnets therein, said magnets connected in parallel through said board, an electrically-conductive card and means to close circuit through each magnet independently of the others in yielding contact with 95 said card, substantially as described.

6. In an electrical jacquard mechanism, the combination with the needles and needle-board, of a magnet-board, electromagnets therein connected in parallel, a contact-board, electrical contacts therein for each magnet, fingers each connected with a contact and organized to close circuit through its respective contact and magnet, and a template formed to control circuits through the electrically-connected parts, substantially as described.

7. In an electrical jacquard mechanism, the combination with the needles and needle-board, of a contact-board and contacts therein, a magnet-board between said contact and needle-boards in electrical connection with the former and operative position to the latter, a second contact-board and contacts therein each in electrical connection with a 115 contact of the first-mentioned contact-board, fingers each in electrical connection with a contact in the second contact-board and means for closing circuit through the fingers and electrically-connected parts, thereby energizing the magnets and operating the needles, substantially as described.

8. In electrical jacquard mechanism, a selector or circuit-closer, comprising stationary members and a detachable rotatable finger 125 for each stationary member, substantially as described.

9. In electrical jacquard mechanism, a selector or circuit-closing device, comprising a contact-board and spring-contact therein, stationary members each in electrical connection with a spring-contact, and detachable fingers hinged to the stationary members rotatable thereon, substantially as described.

10. In electrical jacquard mechanism, a selector or circuit-closing device, comprising a contact-board and contacts therein, stationary members each in electrical connection with a contact in said board, said board and contacts removable from the device, and detachable fingers hinged to said fixed members, substantially as described. 5
11. In electrical jacquard mechanism, a selector or circuit-closer, comprising a contact-board and contacts therein, vertical fixed members each in electrical connection with a contact in said board, and bent ends on said vertical members and fingers hinged on said 15 bent-up ends, substantially as described.
12. In electrical jacquard mechanism, a selector or circuit-closing device, comprising a contact-board and contacts therein, stationary members each in electrical connection 20 with a contact in said board, and detachable fingers hinged to the stationary members, substantially as described.
13. In electrical jacquard mechanism, a selector or circuit-closer, comprising stationary 25 members a projection on each member, contacts arranged to close circuit through said member and projection, a bent-up lower end on each member and a finger hinged to said bent-up member, substantially as described. 30
14. In electrical jacquard mechanism, a selector or circuit-closer, comprising vertical stationary members having their lower ends bent up at an angle, a circular enlargement on said end having parallel cut-away portions, detachable fingers provided with a circular notch at one end greater than a semi-circle and organized to detachably connect said fingers to the enlargement on the stationary members, substantially as described. 35
15. In electrical jacquard mechanism, a magnet-board electromagnets therein each magnet comprising a core, a conductive contact-button insulated from said core, a winding for said core, one end of said winding in 40 electrical connection with said button, substantially as described.
16. In electrical jacquard mechanism, a needle-operating electromagnet, comprising a metallic core, a hollow contact-button insulated from and connected thereto, a winding 50 for said core, one end thereof connected to said button and the other to said core, and a conductive core for the magnet, substantially as described. 55
17. In electrical jacquard mechanism, a needle-operating electromagnet, comprising a metallic core, a hollow contact-button insulated from and secured to one end of said core, a winding on said core one end connected thereto and the other to the insulated 60 button, and a metallic cover for the magnet connected to the core and adapted to complete the return-circuit, substantially as described. 65
18. In electrical jacquard mechanism, the combination with a magnet-board, comprised of a conductor of electricity, of magnets comprising a core; an insulated button connected thereto, a winding on said core one end thereof connected to the magnet-core and the other 70 to said button, and a metallic cover for said magnet secured to the core and designed to complete electrical circuit from the button through the winding and casing to the magnet-board, substantially as described. 75
19. In electrical jacquard mechanism, the combination with the needles and needle-board, of a series of stationary magnets arranged to operate said needles, a series of fingers each in electrical connection with a 80 magnet, a flat platen horizontally movable under said fingers and having insulated and conductive portions on its surface, and a contact for the under side of said platen, substantially as described. 85
- In testimony that I claim the foregoing as my invention I have signed my name in presence of two subscribing witnesses.
